UNITED STATES PATENT OFFICE.

WILLIAM N. SYMINGTON, OF BROOKLYN, NEW YORK.

COAL-CUTTING MACHINERY.

SPECIFICATION forming part of Letters Patent No. 413,796, dated October 29, 1889.

Application filed June 5, 1889. Serial No. 313,188. (No model.)

To all whom it may concern:

Be it known that I, WILLIAM N. SYMINGTON, a citizen of the United States, and a resident of Brooklyn, Kings county, New York, 5 have invented Improvements in Coal-Cutting Machinery, of which the following is a specification.

The object of my invention is to so construct a portable coal-cutting machine that 10 when in use the coal-dust will not go into the power-transmitting devices, and that consequently the machine will last longer and do its work better.

My invention also relates to certain improvements in the detailed construction of 15 the transmitting devices and of the cutters.

In the accompanying drawings, Figure 1 is a longitudinal section of my improved coal-cutting machine. Fig. 2 is a sectional plan view. Fig. 3 is a vertical section, drawn to an enlarged scale, of the cutters mounted in the outer end of the carrying-arm. Fig. 4 is a corresponding plan view, but with the top plate removed. Figs. 5 and 6 are corresponding 20 views of a modified form of cutter. Fig. 7 is a transverse section of the carrying-arm of the cutter on the line 1 2, Fig. 1. Fig. 8 is a side view, partly in section, of a modification.

30 My invention relates to that class of coal-cutters in which the machine is mounted upon a pair of wheels and has a frame extending out in front of the wheels several feet and carrying at its outer end rotary cutters, while the opposite end of the frame carries the motor for driving the cutters.

Referring to Figs. 1 and 2, A A are the pair of wheels on which the machine is mounted, and B is the frame having the forwardly-extending arm B', which carries at its outer end the pair of rotary cutters D D, while at the opposite end of the frame is shown the casing E for the motor for driving the rotary cutters. This motor may be either a compressed-air motor of any suitable construction or an electric motor, or any other motor which may be found adapted for use in this connection. I have, however, thought it unnecessary to illustrate the details of the motor, as they form no part of my present invention. I need only here state that e is in-

tended to represent the driving-shaft of the motor, which, in the construction shown in Figs. 1 and 2, carries the flanged wheel or pulley E' for transmitting motion by means of an endless rope, belt, or band to a corresponding, but smaller, flanged wheel or pulley F on the vertical axis f, which carries the two rotary cutters on the upper and lower sides of the carrying-arm B'. The endless rope, belt, or band, 55 which may conveniently be a wire rope, is passed twice around each of these wheels or pulleys E' and F, and also once partially around a tightening-pulley G, mounted in bearings in the adjustable block H on guides 60 h in the frame of the machine. This block, carrying the idler-pulley G, may be adjusted longitudinally in the frame, to tighten the endless rope, belt, or band, by means of a longitudinal feed-screw S, adapted to turn in 65 the fixed bearings s in the frame and having its end adapted to a corresponding opening in the block H.

While I prefer the described means of transmitting motion from the motor to the 70 rotary cutters, I do not, however, wish to confine myself thereto in all cases, as other means may be used—such, for instance, as the longitudinal shaft T, (shown in the modification, Fig. 8,) with a bevel-pinion k at its outer end 75 gearing into a bevel-wheel F' on the axis F of the cutters. Whatever may be the means of transmission, however, it is an important feature of my invention that the entire frame B, especially the extended arm B', shall be 80 in the form of a closed box or case, which shall entirely surround and inclose the driving-gear and the wheel on the axis for the 85 rotary cutters, this axis extending through suitable bearings in the outer end of the inclosing-frame, as shown more fully in Figs. 3 and 5. By thus constructing the frame in the 90 form of a closed box, as shown in Figs. 1, 2, and 7, the coal-dust, when the machine is in use, cannot get into and clog up the working 95 parts, as is the case in coal-cutters of ordinary construction, and in consequence the machine will work for a much longer time without attention or repairs than will machines as heretofore used. This construction of closed 100 frame also has the advantage of being comparatively light for a given strength. The

closed box also enables me to provide for the internal lubrication by pouring a supply of oil into the bottom of the inclosed case, and as the machine is tilted up and down more or less when in use this oil will find its way to the different bearings and avoid the necessity of lubricating from outside.

I prefer in carrying out my invention to construct the cutters in the detailed manner illustrated in Figs. 3 and 4. In this case each rotary cutter consists of a number of coal-cutting tools K, (three in this case being shown on each cutter,) fitting in corresponding recesses in the disk A', which is keyed to the vertical axis f. The top plate k², which is held down on the disk by a nut k' and by means of suitable bolts and nuts, holds the several cutters in place vertically, while they are held lengthwise by ribs r on the top plates and the bottoms of the recesses fitting into corresponding notches in the edges of the cutters.

In the construction illustrated in Figs. 5 and 6 I have shown the cutting-tools with cutting-edges of a slightly-different form from those shown in Fig. 4, and there are six tools on each cutter. In other respects the cutters in this modification are substantially like those already described.

I am aware that inclosed casings have been used in mining-machines with reciprocating drills and with augers, and I do not wish to be understood as desiring to claim, broadly, the inclosing of operating mechanism in mining machinery; but

35 I claim as my invention—

1. A coal-cutting machine having a pair of rotary cutters and driving mechanism therefor, and having the frame in the form of a closed box entirely inclosing the driving mechanism, and an axis passing through the outer

end of the box and carrying within the latter a wheel to receive the driving-power, while on the outside the axis carries the two rotary cutters.

2. The combination of the motor of a coal-cutting machine with driving mechanism and the frame in the form of a closed box inclosing the motor and the mechanism for transmitting motion from the motor, and an axis passing through the outer end of the box and carrying within the latter a wheel to receive the driving-power, while on the outside the axis carries two rotary cutters.

3. The combination of a coal-cutting machine having its entire frame in the form of a closed box, a vertical driving-shaft, and pulley at one end of the frame, with a vertical axis passing through the outer end of the frame and carrying within the latter a pulley and carrying rotary cutters outside the frame, and an endless rope transmitting motion from one pulley to the other, the said frame inclosing the rope and pulleys, all substantially as described.

4. The combination of the frame of a coal-cutting machine having a motor, driving-shaft, and wheel, with a vertical axis having a central wheel, a pair of rotary cutters, and an endless rope passed twice around both of said wheels, and an adjustable idler-pulley around which the rope is also passed, all substantially as set forth.

In testimony whereof I have signed my name to this specification in the presence of two subscribing witnesses.

WILLIAM N. SYMINGTON.
